(57) **CLAIM**

The ornamental design for a feeding bottle for a large mammal, as shown and described.

DESCRIPTION

FIG. 1 is a front-perspective, exploded view of the first embodiment of a feeding bottle for a large mammal.

FIG. 2 is a bottom perspective view of FIG. 1, but shown separate from the nipple feature for clarity of illustration.

FIG. 3 is a front view thereof;

FIG. 4 is a right view thereof;

FIG. 5 is a top view thereof;

FIG. 6 is a bottom view thereof;

FIG. 7 is a front perspective view of the second embodiment of a feeding bottle for a large mammal.

FIG. 8 is a bottom perspective view of FIG. 7, but shown separate from the nipple feature for clarity of illustration.

FIG. 9 is a front view thereof;

FIG. 10 is a right view thereof;

FIG. 11 is a top view thereof;

FIG. 12 is a bottom view thereof;

FIG. 13 is a front perspective view of the third embodiment of a feeding bottle for a large mammal.

FIG. 14 is a bottom perspective view of FIG. 13, but shown separate from the nipple feature for clarity of illustration.

FIG. 15 is a front view thereof;

FIG. 16 is a right view thereof;

FIG. 17 is a top view thereof; and,

FIG. 18 is a bottom view thereof.

1 Claim, 15 Drawing Sheets
